KNITTING MACHINE

Albert E. Stewart, Franklin, N. H., assignor to
 Acme Knitting Machine & Needle Company,
 Franklin, N. H., a corporation of New Hampshire

Application August 7, 1923, Serial No. 656,160

14 Claims. (Cl. 66—133)

This invention relates to knitting machines and more especially to the thread feeding mechanisms of such machines.

In the knitting of women's hosiery it has been customary to reinforce that portion of the hose immediately above the heel, this reinforcement being commonly referred to in the trade as a "high splice". It has also been proposed to make this splice or reinforcement very narrow at the top and gradually increase its width as it approaches the heel, thus producing what is known as a "tapered high splice". The present invention is especially concerned with the production of a splice or reinforcement of this character, although it is also contemplated that the mechanism used in making such a splice can be used in other types of machines than hosiery knitting machines. It is the chief object of the invention to devise a simple and reliable mechanism for producing a splice or reinforcement of the character above described.

The invention will be herein disclosed as embodied in a circular hosiery knitting machine of the character shown and described in Canadian Patent No. 200,057, granted May 11, 1920, and it is an object of the invention to devise an attachment for this machine with the aid of which a tapered high splice can be produced automatically while, at the same time, retaining all the other advantages of the machine.

The nature of the invention will be readily understood from the following description when read in connection with the accompanying drawings, and the novel features will be particularly pointed out in the appended claims.

Referring now to the drawings, Figure 1 is a front elevation of the machine shown in the patent above designated equipped with mechanism embodying this invention; Fig. 2 is a side elevation of the machine shown in Fig. 1 showing the entire thread feeding mechanism provided by this invention, certain parts of the machine, however, being omitted; Fig. 3 is a cross sectional view on the line 3—3, Fig. 2;

Fig. 4 is a front elevation of the more important parts of the mechanism that controls the period of operation of the reinforcing thread feeding device in each knitting course; Fig. 5 is a side elevation of the mechanism shown in Fig. 4; and

Fig. 6 is a plan view of one of the cam members used in the machine.

Referring more particularly to Figs. 1 and 2, the machine shown comprises a rotating needle

cylinder 2 carrying a series of needles, one of which is shown in dotted lines at 3 in Fig. 2. A detailed description of the machine is unnecessary to an understanding of the present invention, but reference should be made for such a description to the patent above designated. The reinforcing thread feeding device is indicated at 4, Fig. 2. It comprises a lever fulcrumed on the machine frame at 5 and provided at its lower end with a thread guiding eye through which the reinforcing thread T is guided to the needles. A spring 6 tends to hold this device in its operative position, as shown in Fig. 2, where it will feed thread to the needles, but it can be moved toward the right, Fig. 2, into an inoperative position where it holds the thread out of the range of action of the needles. For this purpose a lever 7 is fulcrumed on an arm 8 which is pivoted on the machine frame at 10. The upper end of this lever is arranged to bear against the lower part of the thread feeding device or finger 4, while the lower end of the lever is connected by a link 12, bell crank 14 and rod 15 to a lever 16 which is fulcrumed on the machine frame at 17.

In this machine the stocking is knit from the top toward the toe, and the thread feeding device is moved both into and out of its operative position during each knitting course while the splice is being made, the length of time which it remains in its thread feeding position being gradually increased so that it supplies thread at first to a very few needles and gradually increases the number of needles so supplied in successive knitting courses until a splice of the maximum width is produced.

For this purpose the lever 16 is rocked by two cam members which jointly act to determine the period of operation of the thread feeding device in each knitting course. Referring more particularly to Figs. 4 and 5, these cam members are indicated at 20 and 21, respectively. A roll 22 mounted on the right-hand end, Figs. 2 and 4, of the lever 16 runs on the peripheral surfaces of both cam members. These members are each of substantially the form shown in Fig. 6, and they are mounted to rotate both in unison and also with reference to each other so that the relationship of the high and low portions of the cams can be changed. These parts are shown in Fig. 4 in substantially the relationship they occupy at the beginning of the reinforcing operation, and it will be seen that the inclined ends 22' and 23 of the high portions of the cams are separated by a very short distance or gap into which the roll 22 may drop momentarily. The cam members are

rotated in opposite directions so that the width of the gap is gradually increased as the knitting operation progresses.

This relative rotative movement is effected 5 through a pawl and ratchet mechanism comprising ratchet wheels 24 and 25 which are secured, respectively, to the cam members 20 and 21. All of these parts are mounted to rotate on a sleeve or bushing 26, Fig. 3, which is secured to the projecting end of the shaft 27, Figs. 1 and 3, of the machine. This shaft is rotated continuously during circular knitting and the ratchet wheels and cams rotate with it. Secured to the forward end of the shaft 27 is a frame or spider 28 having a 10 long slot 30 in one arm thereof. A slide 31 is mounted to reciprocate in this slot and has pawls 32 and 33 pivoted to its upper end and arranged to engage, respectively, with the teeth of the ratchet wheels 24 and 25. A coiled spring 34 connects the two pawls and tends to draw them 15 toward each other. Pivoted at 35 on the slide 31 is a latch 36 having a shoulder which normally engages a pin 37 fastened in the upper end of the frame 28. A spring 38 connects the pin and the 20 latch in such a manner that it performs the double function of holding the latch normally against the pin and also of drawing the slide 31 toward the outer end of the slot 30, this movement, however, being limited by the latch 36 25 and pin 37.

For the purpose of producing an inward movement of the slide 31, a pinion 40 is mounted on a stud 41 co-axially with the shaft 27 and is secured to the end of an arm 42. This arm is held 30 against rotation by a pin 43 projecting from the machine frame. Meshing with the pinion 40 is a gear 44 mounted on a stud 45 which is supported by a strap 46 secured to the frame 28. A cam 47 is secured to the back of this gear and is arranged to engage a roll 48 mounted on the lower 35 end of the slide 31.

As above stated, the frame 28 rotates with the shaft 27, and since the pinion 40 is held against rotation, the bodily rotation of the gear 44 with 40 the frame 28 will compel this gear to rotate on its own axis. This revolves the cam 47 and causes it to depress the slide 31 once during two revolutions of the frame. The spring 38 returns the slide again to its initial position. This reciprocation 45 of the slide operates the pawls 32 and 33 and causes them to rotate the ratchet wheels 24 and 25 step by step in opposite directions, and thus to gradually change the relationship of the cam members 20 and 21 with reference to each other.

In order to avoid the necessity of making the teeth of the ratchets or pawls 32 and 33 extremely small, or else of making the teeth of the ratchet wheels very fine, pawls 32' and 33', each half a tooth shorter than the pawls 32 and 33, 50 are located, respectively, immediately behind the latter pawls and are connected by a coiled spring 50. The movement of the slide 31 is only sufficient to bring the individual pawls of each pair alternately into operation, so that each ratchet 55 wheel is moved half a tooth at each reciprocation of the slide. Spring clamps 51-51, screwed to the frame 28, bear against the two ratchet wheels and exert enough frictional resistance to their movement to hold them in adjusted relationship.

70 It will now be understood that as the shaft 27 rotates, the cam members 20 and 31 rotate with it, and that so long as the roll 22 on the end of the lever 16 rides on the high portions of these cam members, the connections between the roll 22 and 75 the thread feeding finger 4 will hold this device

forward in its inoperative position. As soon as the roll 22 drops into the gap between the inclined surfaces 22' and 23 of the cam members, the spring 6 immediately pulls the thread feeding finger 4 back into its operative position. The length of time that the finger remains in this position depends on the width of the gap between the surfaces 22' and 23. This gap is gradually widened by the step by step rotation of the ratchet wheels, as has been explained above, so 10 that the number of needles to which the reinforcing thread will be fed is gradually increased until approximately half of the entire circular series of needles is supplied with reinforcing thread. Usually the operating mechanism for 15 the thread feeding device 4 is so timed that the number of needles to which reinforcing thread is fed is increased in each successive knitting course until the maximum number is reached. This arrangement can be changed, however, by suitable 20 timing so that the increase in the number of needles supplied with reinforcing thread will be made in every other course, or various other combinations can be worked out. The length of the reinforcement is, however, increased in adjacent 25 courses, the increase preferably being the same at each side of the median line at the back of the leg. The splice formed thus is tapered gradually from the desired point at the back of the ankle to the top of the heel. Usually this reinforcement is 30 carried through the lower part of the foot.

The movement of the ratchet wheels may be interrupted at any desired point by cutting out a tooth in each wheel, as indicated, for instance, at 53-53, Fig. 4. In order to initiate this ratcheting movement again, a disk 55, Figs. 1, 2 and 3, is mounted on the end of the pattern drum shaft 56 and a pin 57 carried by this disk is arranged to engage the lower end of a lever 58. The rocking movement produced by such engagement 40 swings this lever far enough to carry a roll 60 on the upper end of the lever into the path of the latch 36. The frame 28 normally rotates in a counter-clockwise direction, Fig. 2, and when the latch strikes the roll it is disengaged from 45 the pin 37, whereupon the spring 38 moves the slide 31 to the outer end of the slot 30. Upon the next rotation of the frame 28 the cam 47 moves the slide 31 to its innermost limit, and this results in imparting an abnormally long stroke 50 to both pawls so that they engage the teeth next adjacent to the cut out teeth, whereupon the normal ratcheting operation is resumed. The latch 36 is reengaged with the pin 37 by the spring 38 during the first inward movement of the 55 slide just described.

The disk 55 is under the control of the pattern mechanism of the machine so that the point at which the ratcheting action is resumed can be varied at will simply by locating a pin 57 properly 60 in the disk. Obviously any desired number of pins may be mounted in the disk 55.

The machine to which this mechanism is applied is equipped with a pattern drum 62, Fig. 2, mounted at the head of the machine. Mechanism is provided to enable this drum to control the reinforcing thread feeding finger 4. For this purpose two lugs 63 and 64 are mounted on the drum 62, and the lug 63 is arranged to engage the lower end of a lever 65 and tip it backwardly into the position shown in Fig. 2. At other times the lever is held forward by a spring 66, and at such times it acts through a slide or bar 67, the forward end of which bears against 70 the thread feeding device 4, to hold this device in 75

- its inoperative position. When the lever 65 is tipped backwardly, it acts through a spring 68 to draw the bar 67 backwardly. The lug 64 is arranged to engage a bell crank lever 70, fulcrumed at 10, and having an arm adapted to bear against a pin 71 which projects laterally from the arm 8. This moves the arm 8 forward and carries the lever 7 forward into position to operate the thread feeding finger 4. It will thus be observed that the drum 62 assumes primary control over the thread feeding device 4 and that the operating mechanism previously described for this device is permitted to act on it only when the lugs 63 and 64 engage their respective levers 65 and 70.
- 15 After the cams 20 and 21 have been rotated into position to effect a reinforcement of the maximum width, it is necessary before another high splice can be made to return the cams to their initial relationship, substantially as shown in Fig. 4. This action occurs after the splice has been completed and while the machine is knitting the leg portion of another stocking, the necessary ratcheting action being initiated through a pin 57, properly placed on the disk 55, and being interrupted again when the cams have been returned to their proper relationship by cut-out teeth in the ratchet wheels.
- It will now be appreciated that this invention provides a simple and reliable mechanism for automatically producing a tapered splice or reinforcement. The mechanism can be manufactured very economically and is readily adaptable to the different conditions encountered in the knitting of hosiery.
- 35 While I have herein shown and described the best embodiment of the invention that I have so far devised, it will be understood that the invention is not limited to embodiment in the particular form shown.
- 40 Having thus described my invention, what I desire to claim as new is:
1. In a hosiery knitting machine, the combination with a reinforcing thread feeding means, of mechanism for determining the number of needles to which said thread will be fed in each knitting course, comprising two rotary cam members jointly controlling the action of said thread feeding means and means to effect a gradual change in their relation to each other during the knitting of the reinforcement.
  2. In a hosiery knitting machine, the combination with a reinforcing thread feeding means, of mechanism for determining the number of needles to which said thread will be fed in each knitting course, comprising two rotary cam members jointly controlling the action of said thread feeding means, and mechanism for gradually changing the circumferential relationship of said members to each other as the knitting operation progresses.
  3. In a hosiery knitting machine, the combination with a reinforcing thread feeding means, of mechanism for determining the number of needles to which said thread will be fed in each knitting course, comprising two rotary cam members arranged to act jointly on said means, and mechanism for effecting a step by step change in the circumferential relationship of said members to each other as the knitting operation progresses.
  4. In a hosiery knitting machine, the combination with a reinforcing thread feeding device, of mechanism for controlling the period of operation of said device in each knitting course comprising two rotary cam members jointly controlling said device, and mechanism for gradually changing the circumferential relationship of said members to each other as the knitting operation progresses.
5. In a hosiery knitting machine, the combination with a reinforcing thread feeding device, of mechanism for operating said device to vary the length of the reinforcement in adjacent courses, comprising two rotary cam members, connections arranged to be operated jointly by said members for moving said device, and mechanism for relatively rotating said cam members to gradually change their action on said device.
6. In a hosiery knitting machine, the combination with a reinforcing thread feeding device, of mechanism for operating said device to vary the length of the reinforcement in adjacent courses, comprising two rotary cam members, connections arranged to be operated jointly by said members for moving said device, and mechanism for giving said members an operative rotary movement and for gradually changing their relationship to each other.
7. In a hosiery knitting machine, the combination with a reinforcing thread feeding device, of mechanism for operating said device to vary the length of the reinforcement in adjacent courses, comprising two rotary cam members, connections arranged to be operated jointly by said members for moving said device, mechanism for rotating said members in unison, and additional means for giving said members a relative rotative movement to change their relationship to each other.
8. In a hosiery knitting machine, the combination with a reinforcing thread feeding device, of mechanism for operating said device to vary the length of the reinforcement in adjacent courses, comprising two rotary cam members, connections arranged to be operated jointly by said members for moving said device, and additional means under the control of the pattern mechanism of the machine for oppositely rotating said cam members.
9. In a hosiery knitting machine, the combination of a reinforcing thread feeding device, of mechanism for operating said device comprising two rotary cam members mounted side by side, connections arranged to be operated by said cam members for moving said device from one of its positions to another, two ratchet wheels secured, respectively, to said members, and a pawl mechanism for rotating said wheels step by step in opposite directions.
10. In a hosiery knitting machine, the combination of a reinforcing thread feeding device, of mechanism for operating said device comprising two rotary cam members mounted side by side, connections arranged to be operated by said cam members for moving said device from one of its positions to another, two ratchet wheels secured, respectively, to said members, a pawl mechanism for rotating said wheels step by step in opposite directions, and means whereby the movement of said wheels may be stopped and started automatically under predetermined conditions.
11. In a hosiery knitting machine, the combination of a reinforcing thread feeding device, of mechanism for operating said device comprising two rotary cam members mounted side by side, connections arranged to be operated by said cam members for moving said device from one of its positions to another, two ratchet wheels secured, respectively, to said members, a

pawl mechanism for rotating said wheels step by step in opposite directions, and means for automatically initiating the action of said pawl mechanism at a predetermined point in the cycle of operations of the machine.

12. In a hosiery knitting machine, the combination with a reinforcing thread feeding device, of mechanism for operating said device to vary the length of the reinforcement in adjacent courses, comprising two rotary cam members, connections arranged to be operated jointly by said members for moving said device from one of its positions to the other, mechanism for relatively rotating said cam members to gradually change their relationship to each other, means whereby the relative rotation of said cam members may be started and stopped automatically at any desired points in the cycle of operations

of the machine, and additional mechanism under the control of the pattern mechanism of the machine for operating said device.

13. A circular knitting machine, having needles and yarn guides, including a splicing yarn guide, movable to and from feeding position in combination with a variable cam controlling the movement of the splicing yarn guide, said cam comprising two circumferentially movable members and feed devices to move said members in opposite directions.

14. A circular knitting machine, having needles and yarn guides, including a splicing yarn guide, in combination with a variable cam controlling the splicing yarn guide, said cam comprising two cam disks and feed devices to turn said disks in opposite directions.

ALBERT E. STEWART.
